UNITED STATES PATENT OFFICE.

RAYMOND E. GARVEY, OF IRONWOOD, MICHIGAN.

ATTACHMENT FOR BOILERS.

Application filed July 28, 1928. Serial No. 225,554.

This invention relates to heating systems and more particularly to an attachment for boilers.

Broadly speaking it is an important object 5 of the invention to provide means for utilizing the heat of the products of combustion and flue gases for heating the boiler and to utilize the products of combustion and flue gases for preventing radiation of heat from 10 the boiler.

A further object is to provide a casing adapted to surround a portion of a boiler and provided with passages through which the products of combustion and flue gases are 15 adapted to flow in contact with the boiler before passing out through the stack.

A further object is to provide a heat insulating casing surrounding a portion of a boiler and provided at its sides with relatively 20 narrow deep passages for the flue gases whereby the latter are held in close proximity to the boiler to heat the latter and prevent radiation therefrom before the flue gases pass to the stack.

25 A further object is to provide a device of the above mentioned character provided with suitable dampers for controlling the passage of the gases.

Other objects and advantages of the invention 30 will become apparent during the course of the following description.

In the drawings I have shown one embodiment of the invention. In this showing:

Figure 1 is a side elevation of a boiler 35 showing the device applied, parts being broken away,

Figure 2 is a section on line 2—2 of Figure 1,

Figure 3 is a section taken substantially on 40 line 3—3 of Figure 1, and,

Figure 4 is a horizontal section on line 4—4 of Figure 1, the furnace being shown in elevation.

Referring to the drawings the numeral 10 45 designates an ordinary furnace, preferably of the oil or gas burning type. The furnace is provided in its front end with a fire door 11 and an ash pit door 12. Clean out doors 13 of the usual type also are provided to permit the flues of the furnace to be cleaned out.

The furnace is provided with a stack or outlet pipe 14 adapted to be controlled by the usual damper 15.

Inner and outer metal casings 16 and 17 50 surround the top, sides and back of the furnace in spaced relation thereto as clearly

shown in Figures 2 and 4. The casings 16 and 17 form in effect a single casing having parallel walls slightly spaced, and this space may be utilized either as a dead air space or 55 may be filled with heat insulating material as indicated at 18. The forward end of the casing is provided with an inwardly extending wall 19 snugly fitting against the sides of the furnace adjacent the front thereof 60 whereby the latter is accessible in the usual manner for firing the boiler or furnace. At the sides of the furnace a relatively narrow passage 19' is provided inwardly of the casing, and this passage extends throughout 65 the height of the furnace. Rearwardly of the furnace, a relatively deep space 20 is provided. This space communicates with an outlet pipe 21 closed at its outer end by a 70 cap 22. A branch pipe 23 connects the pipes 21 and 14 and may be controlled by a suitable damper 24.

Inwardly of the casing, a horizontal plate 25 surrounds the furnace adjacent the top thereof, and below the plate 25 another plate 26 or partition 26 extends from the rear end of the casing to a point spaced from the forward end thereof as indicated at 27, whereby the passage 19' is divided into passages or flues 28 and 29 for a purpose to be described. As shown in Figure 3, the plates 25 and 26 extend from the back of the furnace to the back wall of the casing.

Means are provided for permitting the flue gases to pass into the passage 28 instead 90 of passing directly to the stack. For this purpose, branch pipes 30 are connected with the stack 14 and extend into opposite sides of the space between the plates 25 and 26, rearwardly of the furnace. Dampers 31 are 95 adapted to control the passage of gases through the pipes 30 and these dampers are controlled by handles or knobs 32.

As shown in Figure 2, the passage 29 extends from the plate 26 to the floor line, and clean out openings 33 are provided in the casing and adapted to be closed by covers 34.

The operation of the device is as follows:

As previously stated, the attachment is 100 particularly adapted for use in connection with heating plants employing oil or gas burning equipment but is not necessarily limited to such use. When the furnace is in operation, the damper 15 may be closed, and the dampers 31 opened. The products of combustion will flow through the pipes 30 to the rear portions of the passage 28, and

thence forwardly through the sides of these passages as indicated by the arrows in Figures 2 and 3. When the forward end 27 of the partition 26 is reached, the gases flow 5 downwardly into the lower passage 29, to the rear portion of the passage 29, and thence to the stack through pipes 21 and 23, it being understood that the damper 24 is employed in place of the damper 15 and is 10 regulated in accordance with the usual practice. It will be apparent that the passages 28 and 29 are formed relatively narrow whereby the products of combustion will be spread throughout the height of the furnace 15 to heat the water therein. The cross sectional areas of the passages are sufficient, however, to permit the free flow of the products of combustion without offering any resistance thereto, whereby the fire may be 20 forced in the usual manner when the damper 24 is opened to permit complete combustion to take place. It will be obvious however, that the dampers 31 may be closed and the damper 15 opened to permit the furnace 25 to be operated in the usual manner. Accumulations of solid matter may be removed from the casing by removing the covers 34 as will be obvious. From the foregoing it will be apparent that the presence of the 30 gases in proximity to the furnace tends to prevent the radiation of heat therefrom.

while the heat of the products of combustion, which is ordinarily wasted is employed to assist in heating the water in the boiler. Radiation of heat also is minimized owing 35 to the use of the insulating material 18, but it has been found that the provision of a dead air space between the inner and outer casings also provides excellent results in this connection.

It is to be understood that the form of the invention herewith shown and described is to be taken as a preferred example of the same and that various changes in the shape, size and arrangement of parts may be resorted to without departing from the spirit 40 of the invention or the scope of the subjoined claim.

I claim:

The combination with a boiler having an 50 outlet opening and a flue, of a casing surrounding a portion of the boiler and provided with a passage arranged in proximity to a portion of the boiler, branch conduits connecting said outlet with one end of said 55 passage at opposite sides of said boiler, the opposite end of said passage being connected to said flue, and dampers in each of said branch conduits for selectively regulating the flow of gases to each side of said boiler. 60

In testimony whereof I affix my signature.

RAYMOND E. GARVEY.
